MECHANISM FOR RETARDING THE RATE OF FIRE OF AUTOMATIC FIREARMS

John J. Maciejowski, Ipswich, Mass., assignor to United Shoe Machinery Corporation, Flemington, N. J., a corporation of New Jersey

Application June 24, 1944, Serial No. 541,896

8 Claims. (Cl. 89—130)

1

This invention relates to firearms and more particularly to mechanism for varying the cyclic rate or rate of fire of automatic guns.

In tracking a target in combat, a machine gunner relies to a considerable extent upon his observation of tracer bullets, one of which is commonly fired after every two regular bullets. In training it is desirable that the visual effect of the tracer bullets be approximately the same as in combat. In order, however, to save ammunition as well as to increase the life of the gun and the target and to enable the gun to be fired for long periods at a time without overheating, it has been suggested that the normal rate of fire of the gun be reduced by two-thirds and that only tracer bullets be used. Under such conditions a sufficient number of tracer bullets are fired at a burst to register hits on the target and the firing has the same visual effect as in combat. It has been further suggested that the rate of fire of the gun could advantageously be reduced to one-ninth its normal rate and only tracer bullets be used, with a view to increasing the target tracking ability of the student after he has reached a high degree of proficiency.

Various devices have been proposed for reducing the rate of fire of automatic guns having fairly constant recoil by retarding, for example, a portion of the counter-recoil movement of a member operatively connected to a breech block of the gun. In some of such devices the distance through which the retarding force acts upon such member during the counter-recoil of the gun varies in accordance with variations in the amount of recoil of said member, with the result that the rate of fire of the gun changes continuously and unpredictably. In other devices proposed for use in connection with guns having substantially constant recoil, a recoil-actuated reciprocating member is coupled at the end of its recoil movement with a retarding device which acts on said member for a fixed distance during counter-recoil movement of the gun. Should such a cyclic rate regulating mechanism be used on a gun having a recoil-actuated member recoil movement of which varies considerably, said member, except when recoiled a minimum distance, would gain considerable momentum during the first part of its counter-recoil movement before being restrained by the retarding device, with the result that there is considerable impact strain on the operating parts and the retarding influence of the device upon the breech block will, to a considerable extent, depend upon the amount of initial kinetic energy of the parts before en-

2

gaging or being picked up by the retarding device.

Retarding devices such as above referred to may be used with a fair degree of accuracy where the recoil movement of the breech block, and therefore said member connected to the block, is substantially constant, but in firearms such as the Oerlikon gun, for example, in which the recoil varies considerably, it has been found that such devices cannot be effectively used for accurately reducing and keeping constant the rate of fire of said gun for the purposes above outlined.

With the above considerations in view, it is an object of the present invention to provide, in an automatic gun the amount of recoil of which varies considerably, a device for selectively controlling the rate of fire of the gun and for maintaining said rate constant for the purpose of training gunners.

With the above object in view and in accordance with a feature of the present invention, the illustrative gun comprises a recoil-actuated member having a recoil movement the rearward extent of which varies considerably, a check, a coupling constructed and arranged to connect the check to said member substantially at the end of its recoil movement irrespective of the extent of such movement, and mechanism for disconnecting the coupling from said member after said member has moved a constant distance from its recoiled position.

In the illustrative device, which is described with reference to the Oerlikon gun, the recoil-actuated member has the form of a ratchet rod which is provided with two series of teeth and is secured to one of the breech bars of the gun. During the breech bar recoiling movement, the extent of which varies considerably, sloping backs of the teeth of the ratchet rod engage and slide rearward over the sloping backs of opposed teeth of a pair of pawls pivoted upon a carrier, forcing said pawls apart against the action of a spring opposite ends of which are secured to the pawls, respectively. The pawl carrier is mounted in a rectilinear guideway of a housing secured to a cradle of the gun and, in accordance with another feature of the invention, is operatively connected through yieldable mechanism comprising Belleville washers to the check which comprises a buffer piston the motion of which in one direction from a retracted idle position is retarded hydraulically. The retarding effect of the piston varies in accordance with the setting of a port-controlling needle valve. The piston, together with the pawl carrier and said yieldable mech-

anism, is normally moved to and held in its retracted starting position by coil springs.

During the recoil movement of the ratchet rod the pawl carrier is held in its retracted starting position by said springs, a cam, which is fulcrumed on the pawl carrier and limits movement of the pawls toward each other, at such time being so positioned that the sloping backs of the teeth of the pawls are engaged by the sloping backs of the teeth of the ratchet rod during recoil movement of said rod. At the start of the counter-recoil movement of the ratchet rod driving faces of the teeth of the ratchet rod are moved into contact with oppositely disposed operating faces of the teeth of the pawls, thereby interlocking or latching the pawls for counter-recoil movement together with the rod. The pawls, which are operatively connected as above described to the piston, retard the first three-quarters of an inch of movement of the ratchet rod from approximately its fully recoiled position, the retarding force being dependent upon the setting of the above-mentioned needle valve.

Just before the ratchet rod has traveled three-quarters of an inch from its fully retracted position, the cam on the pawl carrier is actuated, causing the pawls to swing apart and accordingly to be disconnected from the ratchet rod, with the result that the rod is free to move forward under the propelling force of strong recoil springs operating through said breech bar to which the ratchet rod is secured. After the pawls have been disconnected from the ratchet rod, they are moved back, together with the pawl carrier, the above-mentioned yielding connections, and the piston, by the above-mentioned coil springs to their rearward retracted positions. While the pawl carrier is being retracted, the pawl operating cam is rotated to a position in which it permits the sloping backs of the teeth of the pawls to be engaged by the sloping backs of the teeth of the rod, as above explained, during the next recoil movement of said rod.

It will be apparent from the foregoing that the breech bars of the gun are retarded for three-quarters of an inch from approximately the start of their counter-recoil movement irrespective of the amount of recoil movement of the bars, and also that the counter-recoil movement retarding device becomes effective before the recoiling parts of the gun have had an opportunity to build up any substantial amount of kinetic energy during their counter-recoil movement. By causing the retarding force to act on said parts for a constant distance from approximately the fully retracted position of the parts, it is possible accurately to control the cyclic rate or rate of fire of the gun, even though the recoil movement varies considerably, as in the case of the Oerlikon gun. The construction and arrangement of the device and the ratchet rod are such that the ratchet rod is always released when the rod is rearward of the position it assumes when the gun is cocked, thereby insuring that the retarding movement shall never interfere with the chambering of the cartridge.

The retarding force acting on the ratchet rod through the constant distance of three-quarters of an inch may be varied by changing the size of the needle valve control opening, the rate of fire of the gun being quickly and effectively reduced from its maximum of 450 shots a minute down to 50 shots a minute, for example, if desirable.

The various features of the invention will be understood and appreciated from the following detailed description read in connection with the accompanying drawings, in which

5 Fig. 1 is a side elevation, partly broken away, of an Oerlikon gun provided with the illustrative device;

10 Fig. 2 is a view showing mechanism for clamping the ratchet rod of said device to a breech bar of the gun;

Figures 3 and 4 are exploded views showing in detail the clamping means illustrated in Fig. 2;

Fig. 15 is an angular view of mechanism for rendering the cyclic rate control device inoperative; and

40 Fig. 16 is an enlarged view showing in detail the construction of the teeth of the ratchet rod and pawls through which the device is coupled to the ratchet rod.

45 The illustrative device is described as embodied in an Oerlikon 20 mm. automatic gun mounted upon a cradle 20 (Figs. 1 and 13) and having breech bars 22 (Fig. 1), 24 (Figs. 1 to 6) which are arranged at opposite sides of a barrel

50 26 (Fig. 1), fixed with relation to the cradle, and are secured through a cotter 28 to a breech block (not shown). Slidingly mounted upon flutes 30 of the barrel 26 is a barrel spring casing 32 having lateral studs 34 constructed and arranged for registration in bores 36 at the forward portions 55 of the breech bars 22, 24, the bars being held upon the studs by spring pins 38. Surrounding the barrel are front and rear springs 40, 42 which may be considered a single spring having its forward end centered in the barrel spring casing 32 and its rear end engaging and centralized by a buffer 44.

60 The gun, which fires automatically when a trigger (not shown) is held in a retracted position, is of the full blow-back type, the breech bars 22, 24 sliding rearward upon each discharge of the gun, causing the springs 40, 42 and springs (not shown) of the buffer 44 to be compressed. The cradle 20 is swiveled, for elevating the gun, upon trunnions 46 carried by a yoke 48 which is rotatable upon a pedestal (not shown) about a vertical axis for swinging the gun in azimuth.

65 In order to reduce the rate of fire of the gun, the recoiling parts of the gun are slowed down during the first part of their counter-recoil movement by mechanism which is hereinafter de-

scribed and comprises a ratchet rod 50 secured to the breech bar 24, a check or piston 52 (Figs. 7, 8, 11, 12 and 14), and a reciprocable carrier 54. The carrier 54 is operatively connected to the piston 52 and has mounted upon it a pair of pawls 56 which constitute a latch and at the end of the recoil movement of the ratchet rod 50 are coupled to or interlocked with said rod and are later disconnected from the rod after the rod has moved forward approximately three-quarters of an inch from its fully recoiled position.

Formed integral with the ratchet rod 50 is a bracket 58 (Figs. 1 to 6) a filler piece 60 of which fits in an opening 62 (Figs. 3, 4 and 6) formed in a web 64 of the breech bar 24. The bracket 58 has initially assembled with it an angular thrust piece 66 (Figs. 2, 3, 5 and 6) a flange of which registers in a slot 68 (Figs. 3 and 6) formed in the bracket. The thrust piece 66 may be considered part of the filler piece 60 of the bracket 58 since, as will appear later, said thrust piece serves to force with clamping pressure the rear face 72 (Fig. 4) of the filler piece against the rear end of the opening 62.

The thrust piece 66 is initially secured in the slot 68 of the bracket 58 by a threaded bolt 74 (Figs. 2, 3 and 5) passing through aligned openings in the bracket and the thrust piece, a nut 76 threaded onto the bolt 74, and a screw 78 threaded into the bracket and having its end in engagement with the thrust piece. After the bracket 58, together with the thrust piece 66 assembled therewith, has been mounted upon the breech bar 24 with its filler piece 60 registering in the opening 62 of the web 64 of the bar, the nut 76 and the screw 78 are turned until a face 80 (Figs. 3 and 5) of the thrust piece 66 is forced with slight pressure against the front end of the opening 62 in the web of the breech bar, causing the rear face 72 (Fig. 4) of the filler piece 60 to be forced with slight pressure against the rear end of the opening 62. During such adjustment an offset flat face 82 (Figs. 2, 3 and 5) of the thrust piece 66 lies against the outer face of the web 64 of the breech bar 24.

With the bracket 58 thus mounted on the breech bar 24, a plate 84 (Figs. 2 and 4) is forced with initial pressure against the inner face 85 of the filler piece 60 of the bracket and against the inner face 86 (Fig. 4) of the breech bar by screws 88 which fit in shouldered holes 90 extending through the plate and are threaded into holes 92 in the bracket. In like manner a plate 94 (Figs. 2 and 3) is forced with initial pressure against the inner face of the thrust piece 66 and against the inner face 96 (Fig. 2) of the web 64 of the breech bar 24 by turning screws 98 which fit in shouldered holes 100 extending through the plate and are threaded into holes 102 (Fig. 3) formed in the bracket 58. The nut 76 and the screw 78 are then turned to cause the rear face 72 (Fig. 4) of the filler piece 60 to be clamped with final pressure against the rear end of the opening 62 in the breech bar 24, insuring during such clamping action that the thrust piece 66 shall be properly arranged with its faces 80, 82 (Figs. 2 and 5) in registration with the front end of the opening 62 in the breech bar and the outside face of the web 64 of the bar. With the above construction, the ratchet rod 50, which is formed integral with the bracket 58, is positioned accurately heightwise as well as lengthwise of the breech bar 24. The screws 88, 98 are then finally set up, with the result that the plates 84, 94 secure the bracket 58

with final clamping pressure in its proper position on the breech bar 24.

Each of the pawls 56 is fulcrumed on a pin 108 secured to the pawl carrier 54 and is provided with a lateral ledge 110 normally forced by a spring 112, opposite ends of which are fixed to studs 114 secured to the respective pawls, against a cam 116 secured to a fulcrum pin 117 journaled in the carrier. During the recoil movement of the breech bars 22, 24 the ratchet rod 50 travels rearward between the pawls 56, the sloping backs 118 (Fig. 16) of teeth 120 of the rod engaging the backs 122 of teeth 124 of the pawls and thus moving said pawls apart to permit passage of the rod between them. At the start of the counter-recoil movement of the ratchet rod 50, thrust faces 126 of the teeth 124 of the pawls 56 move into engagement with driving faces 128 of the teeth 120 of the rod, causing the piston 52, which is operatively connected to the carrier 54 through mechanism which will be described later, to be moved to the right, as viewed in Figs. 7 and 8, with the result that oil is transferred from an annular chamber 132 (Figs. 7 and 8) formed between the piston 52 and a cylindrical bore 134 in a block 136, into a reservoir 138 formed in said block. The oil level in the reservoir is indicated by reference numeral 130. The amount of drag on the ratchet rod 50 varies in accordance with the setting of a needle valve 140 (Fig. 7) extending into a narrow passage 142 through which oil passes from the chamber 132 to the reservoir 138. The ratchet rod 50 is retarded only during the first three-quarters of an inch of its counter-recoil movement, the pawls 56, which may be referred to as a latch, being then automatically swung away from each other by the cam 116 to release the ratchet rod, which, actuated by the springs 40, 42, is returned to its forward position, shown in Fig. 1. Upon release of the ratchet rod 50 by the pawls 56, the piston 52 is returned by springs 144 (Figs. 7, 8, 13 and 14) to its initial retracted position, shown in Fig. 7, against a stop plate 146 secured by screws 148 to the block 136. Suction created in the annular chamber 132 by the retraction of the piston 52 causes oil to be sucked from the reservoir 138 to the chamber through pairs of return passages 150 (Figs. 8 and 13), 152 (Fig. 8) provided with check valves 154. To insure against leakage of oil from the annular chamber 132, the piston 52 and the block 136 are provided with annular grooves in which fit packings 156, 158, respectively. When the Oerlikon gun is in a cocked position ready to start firing upon pulling the trigger (not shown), an index mark 159 (Fig. 7) on the ratchet rod 50, which mark is in approximate alignment with roots of the second pair of teeth of the rod, is at the position indicated by dash line 160. Although the recoil of the breech block of the gun varies considerably in accordance, for example, with the power of the charge and the elevation of the gun, such recoil is practically always such that the index mark 159 is moved slightly more than three-quarters of an inch and sometimes as much as one and seven-eighths inches rearward of dash line position 160, in which event the first three-quarters of an inch of counter-recoil movement of the rod is retarded. In order to insure that the cartridge shall be properly chambered, the action of the pawls 56 and the mechanism for releasing them is such that the ratchet rod 50 is always released just before its index mark 159 arrives at the dash line position 160.

Secured to the block 136 by screws 162 (Figs. 7, 8 and 12) and dowels 164 (Figs. 7 and 12) is a pawl carrier housing 166 provided with curved lateral walls 168 (Figs. 12 and 15) which are engaged by and serve as guides for the piston 52, the housing having upper and lower angular guideways 170 (Figs. 7, 8, 12 and 15) for the pawl carrier. The upper and lower portions of the housing 166 are provided with channels 172 for accommodating the pawls 56, which, when they are moved away from each other by the cam 116 to release the ratchet rod 50, move into said channels.

The block 136, together with the carrier housing 166, is secured to the cradle 20 by screws 174 (Figs. 1 and 13) which pass through vertical openings in the cradle and are threaded into the block and the carrier housing. Secured to the forward end of the carrier housing 166 is a filler piece 176 provided with an opening 178 the forward portion of which is beveled and through which the ratchet rod 50 passes.

In order that the pawls 56 shall be interlocked with or latched to the ratchet rod 50 approximately at the end of its recoil movement irrespective of the amount of such movement, it is desirable that the teeth 120, 124 of the ratchet rod and of the pawls be fairly small, considering the load which they have to carry. With a view to insuring against the teeth 120, 124 breaking, the pawl carrier 54 and the piston 52 are connected by a yieldable unit which will now be described. The pawl carrier 54 is threaded onto the forward end of a steel sleeve 182 having a recess 184 (Figs. 7 and 8) for receiving the ratchet rod 50 and having threaded onto its rear end a heavy collar 186. The rear part of the sleeve 182 is somewhat reduced in diameter and forms with an inside cylindrical face 188 (Fig. 7) of the piston 52 an annular space 190. Occupying the forward end of the space 190 and normally in engagement with shoulders 192 (Figs. 7 and 8), 194 of the sleeve 182 and the piston 52, respectively, is a steel drive washer 196, and interposed between the drive washer and the collar 186 are six Belleville spring washers 198.

The forward ends of the springs 144, through which the piston 52 and its associated ratchet rod retarding mechanism are moved back to their retracted positions, are secured in holes formed in rearward projections of the collar 186, the rear ends of the springs being hooked around inwardly extending projections of a retaining plate 200 fitting in a socket of the stop plate 146. When the ratchet rod 50 acting through the pawls 56 first moves the pawl carrier 54 under the restraining influence of the piston 52, the Belleville washers 198 are compressed slightly, as shown in Fig. 8, with a resultant cushioning action between the pawl carrier and the piston and, accordingly, a reduced strain on the coupled-together teeth 120, 124 of the ratchet rod and of the pawls.

When the pawl carrier 54 is in its retracted position, shown in Fig. 7, the pawls 56 are in their closed positions, the lateral ledges 110 of the pawls being held by the spring 112 in engagement with flat faces 202 (Figs. 7, 8, 11 and 14) of the cam 116. Secured to the fulcrum pin 117 by a draw bolt or bill binder 204 (Figs. 9, 10, 14 and 15) is a lever 206 through which the cam 116 is operated to control the action of the pawls 56.

The ratchet rod 50 during the recoil of the breech block of the gun passes through the opening 178 in the filler piece 176 and between the

7
pawls 56 which are wedged apart by the ratchet rod as above described, the rod entering the recess 184 in the sleeve 182. With the ratchet rod retarding assembly in its retracted position shown in Fig. 7, the recess 184 of the sleeve 182 is long enough to accommodate the maximum recoil of the ratchet rod 50, the lines of teeth on the rod being extended sufficiently to co-operate effectively with the pawls 56 for different recoils of said rod.

As above stated, when the ratchet rod 50 starts forward from its fully recoiled position, the driving faces 128 of the teeth 120 of the ratchet rod move into engagement with the faces 126 of the teeth of the pawls, causing the pawl carrier 54 to move forward along the guideways 170 of the housing 166 and, through mechanism above described, to move the piston 52 forward. When this occurs, the oil in the annular chamber 132 is discharged through a passage 208 (Fig. 7) in the block 136 and passages 142, 210 in a valve housing 212 into the reservoir 138 in the block, the drag of the piston 52 being dependent upon the setting of the needle valve 140 in the passage 142. The needle valve housing 212 is constructed and arranged to fit in the block 136 and is secured to the block by one or more screws 214.

Just before the pawl carrier 54 has moved three-quarters of an inch from its fully retracted position, a shoulder 216 (Figs. 10, 14 and 15) of the lever 206 engages a stop 218 (Figs. 1, 7 and 9) fixed to the pawl carrier housing 166, causing the lever to move clockwise, as viewed in Fig. 9, with relation to the carrier, with the result that corner portions 220 of the cam 116 move into engagement with the ledges 110 of the pawls 56, as best shown in Fig. 11, causing the pawls to swing apart, thereby releasing the ratchet rod 50, which then moves forward under the action of the springs 40, 42 to allow the breech block and associated mechanism to chamber and to fire the next cartridge. The pawls 56 release the ratchet rod 50 before the rear end of a slot 222 (Figs. 9, 14 and 15) formed in the lever 206 engages a pin 224 on the pawl carrier 54. At the time the ratchet rod 50 is released, a spring 226, upper and lower ends of which are secured to studs 228, 230 on the housing 166 and the lever 206, respectively, has its axis 231 (Figs. 7, 8 and 9) spaced a considerable distance from the axis of the fulcrum pin 117, as shown in Fig. 9. When the spring 226 is thus positioned with relation to the lever 206, it rotates said lever clockwise, as viewed in Fig. 9, with relation to the carrier 54 and overcomes the tendency of the spring 112 acting through the ledges 110 of the cam 116 to move the lever counterclockwise. The lever 206 is rotated clockwise by the spring 226 until the rear end of the slot 222 engages the pin 224, the lever being temporarily held in such position until the pawl carrier 54 has been moved approximately to its retracted starting position, as will appear later.

As soon as the ratchet rod 50 is released by the pawls 56, the pawl carrier 54 is moved to its retracted position, shown in Fig. 7, by the springs 144, suction created in the annular chamber 132 by the rearward movement of the piston 52 causing the oil to be sucked through the return passage 150 from the reservoir 138, as above described.

During the retractive movement of the pawl carrier 54, the shoulder 216 on the lever 206 engages a stop 232 (Figs. 1, 7, 9, 10 and 15) formed integral with an arm 234, best shown in Figs. 10

and 15, causing the lever to swing in a counter-clockwise direction, as viewed in Fig. 7, with the result that the faces 202 of the cam 116 are brought back into registration with the lugs 110 of the pawls 56, which, as above stated, are constantly urged toward each other by the spring 112. The construction and arrangement is such that this piston 52 engages the stop plate 146 and thus stops further refractive or rearward movement of the pawl carrier 54, the lever 206 at such time, as shown in Fig. 7, having been rotated to a position in which the axis 231 of the spring 226 is arranged in close proximity to the axis of the fulcrum pin 117. When the spring 226 is thus positioned, the ledges 110 of the cam 116 operating under the action of the spring 112 cause the cam to be retained in its idle position in which the flat faces 202 of the cam are in engagement with the ledges.

It will be apparent that immediately after the teeth 124 of the pawls 56 are moved into meshing engagement with the ratchet rod 50 the Belleville washers 198 are compressed, the shoulder 192 (Fig. 8) of the sleeve 182 moving slightly away from the drive washer 196 through which the piston 52 is moved forward. During the continued counter-recoil movement of the ratchet rod 50 the drive washer 196 moves into engagement with the shoulder 192 of the sleeve 182. By providing the above-described cushioning connections, the stress on the teeth 124 of the pawls 56 is reduced to a minimum.

The above-described device may be rendered inoperative, to enable the gun with its trigger held back to be fired at its normal rate, by causing the pawl carrier 54 to be held in its rear or retracted position with the pawls 56 locked in their open positions, the ratchet rod 50 passing in and out of the recess 184 of the sleeve 182 without being engaged by the pawls. With this object in view, the arm 234 (Figs. 10 and 15), provided at its upper end with the lug 232, is mounted on a fulcrum pin 236 which is carried by spaced bosses 238 on the pawl carrier housing 166. When it is desired to render the cyclic rate control device inoperative, a latch pin 240, which holds the arm 234 in its raised operative position, is removed from registering openings in the bosses 238 and the arm. The arm 234 is then swung to its lowered inoperative position shown in dash lines (Fig. 10). With the arm 234 in its inoperative position, it will be apparent that when the open pawls 56 are retracted with the pawl carrier 54 the lever 206 will not be swung as above described to enable the pawls to be moved to their closed positions, with the result that the ratchet rod 50 during its reciprocatory movement passes freely between the pawls and in and out of the recess 184 in the sleeve 182. The cyclic rate control device may be quickly rendered operative at any time by manually swinging the cam control lever 206 forward with relation to the pawl carrier 54, thereby enabling the spring 112 to move the pawls 56 to their closed positions, and by resetting the arm 234 in its operative position shown in Fig. 14.

Having described my invention, what I claim as new and desire to secure by Letters Patent of the United States is:

1. An automatic firearm comprising a recoil-actuated member having a recoil movement which varies to a considerable extent, a check, means for operatively securing said member to said check approximately at the end of the recoil movement of said member irrespective of the

extent of said movement, and mechanism for disconnecting the member from the check after said member has moved a predetermined fixed distance from its fully recoiled position, said means comprising yieldable parts operative after said recoil-actuated member has been operatively connected to the check to insure against excessive strain on portions of said member and portions of said means which are secured together.

5 2. An automatic firearm comprising a recoil-operated reciprocating ratchet rod movable to different fully recoiled positions spaced considerable distances from each other, a check, a carrier mounted for reciprocation, a pair of pawls pivotally connected to the carrier, yieldable connections between the carrier and the check, and means for causing the pawls to be connected to the ratchet rod substantially at the end of the recoil movement of said rod and for causing the pawls to be disengaged from the ratchet rod when said rod has moved a predetermined distance from its fully recoiled position.

10 3. In an automatic gun, a recoil-actuated member having a recoil movement which varies to a considerable extent, a hydraulic check, a latch constructed and arranged to be operatively secured to said member substantially at the end of the recoil movement of said member irrespective of the extent of said movement, yieldable connections between the latch and the check, said connections being operative to yield after the latch has been operatively connected to the check, means for disconnecting the latch from the recoil-actuated member at a fixed predetermined stage in the counter-recoil movement of said member, and means for moving the latch together with said check and said connections back to retracted positions from which they are again moved by said member.

15 4. An automatic firearm comprising a recoil-operated reciprocating ratchet rod, a hydraulic check, a carrier mounted for reciprocation, a pair of pawls mounted upon the carrier, yieldable connections between the pawl carrier and the check, means for causing the pawls to be connected to the ratchet rod substantially at the end of its recoil movement and for causing the pawls to disengage the ratchet rod when said rod has moved a fixed distance forward from its fully recoiled position, and resilient means for returning the pawl carrier, the check, and the yieldable connections back to retracted starting positions after the pawls have been released from the rod.

20 5. In an automatic gun, a reciprocable recoil-actuated member, a ratchet rod secured to said member, a fixed housing having a bore, a piston movable in said bore and forming with the bore a chamber, pawls operatively connected to the piston and constructed and arranged to receive the ratchet rod between them during the recoil movement of said rod, means for coupling the pawls to the ratchet rod substantially at the start of the counter-recoil movement of said rod, a reservoir, a passage for permitting flow of fluid from said chamber to the reservoir during the counter-recoil movement of the rod, a needle valve in said passage, said needle valve being adjustable to vary the amount of resistive force applied by the piston through the pawls to the ratchet rod during its counter-recoil movement, means for disconnecting the pawls from the ratchet rod when said rod has moved a predetermined distance from its fully recoiled position, one or more springs for moving the piston

25 60 65 70 75

together with the pawls back to a retracted starting position, and one or more passages having check valves for permitting fluid to be sucked from the reservoir to the chamber as the piston is moved back to its retracted starting position.

6. In an automatic gun, a recoil spring, a recoil-operated ratched rod movable against the action of said spring, a carrier, a pair of pawls which are fulcrumed on said carrier and are spread apart by the ratchet rod during its recoil movement, a check piston, yieldable connections between the pawl carrier and said piston, cam controlled means for causing the pawls to be coupled for movement with the ratchet rod substantially at the start of its counter-recoil movement and for causing the pawls to release the ratchet rod after it has moved a predetermined distance from its fully recoiled position, and springs for moving said connections, said piston, and said pawl carrier back to their retracted positions after the pawls have been disengaged from the ratchet rod.

7. In an automatic firearm, a recoil actuated member having a recoil movement the rearward extent of which varies considerably, a check, a coupling constructed and arranged to connect the check to said member substantially at the end of its recoil movement irrespective of the extent of such movement, and mechanism for disconnecting the coupling from said member after said member has moved a constant distance from its recoiled position.

8. In an automatic firearm, a recoil actuated member having one or more rows of teeth and a recoil movement the rearward extent of which

varies considerably, a check, a latch operatively connected to the check, resilient means for forcing the latch against the teeth of said member during the latter part of its recoil movement thereby causing the latch to override said teeth during recoil movement of said member and for causing the latch to become locked to said teeth for counter-recoil movement therewith during the first part of the counter-recoil movement of said member, and means for moving the latch against the action of said resilient means away from said teeth when said member has moved a fixed distance from the rearward extent of its recoil movement to disconnect said member from said check.
